UNITED STATES PATENT OFFICE.

JOSEPH AUGUSTE BOURDARIAT, OF PARIS, AND MICHEL DIET, OF VAUCRESSON,
FRANCE.

BUILDING MATERIAL.

1,411,906.

Specification of Letters Patent.

Patented Apr. 4, 1922.

No Drawing.

Application filed March 29, 1921. Serial No. 456,755.

(GRANTED UNDER THE PROVISIONS OF THE ACT OF MARCH 3, 1921, 41 STAT. L., 1313.)

To all whom it may concern:

Be it known that we, JOSEPH AUGUSTE BOURDARIAT, a citizen of the Republic of France, residing at 77 Boulevard Malesherbes, Paris, Seine, France, and MICHEL DIET, a citizen of the Republic of France, residing at Vaucresson, Seine et Oise, France, have invented a new and useful Improvement in Building Material, (for which I 10 have filed application in France April 9, 1919, Patent No. 507,835; Belgium Jan. 31, 1921, Serial No. 22,117; Holland Feb. 4, 1921, Serial No. 17,947, and Denmark March 4, 1921, Serial No. 560,) of which the following is a specification.

It has often been proposed to use sea-wrack, that is to say the marine plant known under the botanical name of "Zostera" in building construction. Its insulating properties, together with its incombustibility and imputrescibility and its insect destroying properties render it a valuable product for building purposes.

Up to the present the wrack has been used 25 in its natural state, being inserted in a sheath. By reason of its elasticity the wrack disintegrates, its fibres being apt to separate easily one from the other. On the other hand the sheath, which is an indispensable element is relatively costly; it is therefore desirable to dispense with it in certain cases.

The present invention also contemplates the use of sea-wrack but introduces an improvement in the manner of such use, in that 35 the sea-wrack instead of being used in its natural state is subjected to an agglomerating process, which, while connecting the fibres together, at the same time leaves air intervals forming cells which contribute to 40 give it good insulating properties.

The characteristic feature of this invention resides therefore in the fact of agglomerating the wrack. This agglomeration can be effected in various ways. The wrack 45 thus agglomerated is available in the form of panels, tiles or plates which can be used to form the covering for walls, ceilings, partitions and for other uses.

In order to agglomerate the wrack any 50 material may be used as agglomerant which has the property of binding the fibres together. By way of example one may mention cement, plaster, pitch, resins, animal

and vegetable glues, silicates. But preferably, the adhesive material extracted from 55 marine plants is employed. The wrack is mixed with this material in variable proportions, say for example, 15 to 25 kilogrammes of the agglutinant material to 100 kilogrammes of dry wrack and the whole is 60 formed into any suitable shape by means of molds. On leaving the mold, the agglomerated wrack is of flat shape of variable thickness which is cut up to form panels, tiles or blocks. The finished product may furthermore be given a cylindrical or other 65 shape in cases where it is desired to form heat- or cold-insulating coverings. Again, the panels, tiles or blocks can be enclosed in a sheath of paper, textile material or the 70 like, thus facilitating their handling and their introduction into sheaths or frames. Owing to the rigidity thus imparted to the wrack by reason of its agglomeration, the panels can easily be nailed in place. 75

Finally when the tiles or panels are applied as a covering to a wall, partition or ceiling they can be fixed, as already stated by nailing, or they can be covered by a facing of wood, fabric, paper or other suitable 80 material.

We claim:

1. An improved building material consisting of sea-wrack (Zostera) in its natural condition and which has been agglomerated.
2. An improved building material consisting of sea-wrack in its natural condition and mixed with an agglutinant.
3. An improved building material consisting of sea-wrack in its natural condition and mixed with an agglutinant extracted from marine plants.
4. An improved building material consisting of 100 parts sea-wrack mixed with 15 to 25 parts of agglutinant.
5. An improved building material consisting of 100 parts of sea-wrack mixed with 15 to 25 parts of agglutinant extracted from marine plants.
6. An improved building material consisting of sea-wrack in its natural condition and mixed with an agglutinant and pressed to shape in molds.
7. An improved building material consisting of agglomerated sea-wrack contain-

ing its natural insoluble mineral and other substances usually present, substantially as described.

8. An improved building material consisting of agglomerated sea-wrack containing its natural mineral and other substances usually present, mixed with an agglutinant.

9. An improved building material con-

sisting of sea-wrack containing its natural mineral and other substances usually present, admixed with an adhesive extraction from marine plants, substantially as described.

JOSEPH AUGUSTE BOURDARIAT.

MICHEL DIET.
